UNITED STATES PATENT OFFICE.

ARNOLD W. MILLER, OF PITTSBURGH, PENNSYLVANIA, ASSIGNOR TO C. HOWARD HOOK, OF PITTSBURGH, PENNSYLVANIA.

RELIEF VALVE.

Application filed June 23, 1921. Serial No. 479,902.

To all whom it may concern:

Be it known that I, ARNOLD W. MILLER, a citizen of the United States, and a resident of Pittsburgh, in the county of Allegheny and State of Pennsylvania, have invented a new and useful Improvement in Relief Valves, of which the following is a specification.

This invention relates to that class of devices known as relief valves or traps principally employed in connection with steam heating systems to discharge the water of condensation, air and other fluids from the system without unnecessary waste of steam.

This invention has for its object to produce a simple and durable device of the class referred to in which the float employed therein for actuating the valve member proper is not subjected to undue lateral impacts by the entrance of the fluids into the valve casing from the heating system, thus rendering the float and attached valve at all times readily responsive to the level of the condensate collected in said casing, reducing the friction between the valve stem and the means for guiding the same, and assuring a proper seating of the valve at all times.

Further objects of the invention are to provide a device which will operate effectively, that is, will be sensitive regardless of the employment of guiding means to maintain the float and valve in alignment, and to provide a self-feeding valve so as to eliminate the troubles resulting from the sticking of the same.

Still further objects are to provide a construction wherein a passage for the air or gaseous medium to be discharged is constantly maintained and to provide means whereby the float chamber may be readily cleaned or drained without disturbing the installation of the device and without interrupting its functioning.

An embodiment of the applicant's invention is illustrated in the accompanying drawing wherein like reference characters denote corresponding parts throughout the several views, in which Fig. 1 is a vertical sectional view through applicant's device, and Fig. 2 a transverse section taken on the line II-II in Fig. 1.

Referring to the drawing Fig. 1 denotes a casing having a removable top 2 provided with spaced lugs 3 for limiting the upward

movement of a float 4, the upper end of which is connected by the hollow stem 5 to a conical valve 6 which coacts with a seat 7. The seat 7 is located upon the inner edge of a raised annular rib 7' surrounding the discharge opening 8 in the bottom of the casing. The rib 7' is of sufficient height to maintain a substantial quantity of sealing liquid to effectively seal the by-pass valve 9 and to prevent sediment collecting in the bottom of the casing passing through the main valve and discharge opening. The valve 9 is located in the by-pass 10 connecting the annular trough 12 formed between the rib 7' and the sides of the casing 1 and the interior of a hollow extension 11 depending therefrom. By opening valve 9 sediment which has collected in the bottom of the casing may be discharged directly into the pipe connected to the extension 11, the same being also used to provide a free passage for the fluids in case the valve 6 becomes stuck or otherwise disabled. When the valve 9 is in closed position, the liquid collected in the annular trough 12 acts to seal said valve and to prevent the return of fluid therethrough. The passage in the hollow stem 5 is continued through the body of valve 6 and permits the passage of air or other gaseous medium to the discharge opening 8. The casing 1 is provided at its outlet side with an offset enlargement 12' which extends substantially the full height of the casing and the inlet 13 connects with this enlargement at its upper end, the said inlet being connected by a union 14 to the pipe (not shown) leading from the heating system.

The external diameter of the float is somewhat less than the internal diameter of the casing so as to form an annular passage 15 which, in conjunction with the spaces between the spaced lugs 3 maintain a constantly open passage for the gaseous medium between the inlet 13 and hollow stem 5.

The float and valve stem are guided vertically by the rod 16 which, as shown, is of circular cross-section and smaller than the passage in hollow stem 5 to permit the passage of fluids around the same and a slight lateral movement of the float.

The guiding means illustrated permit a slight lateral movement of the float and at-

tached parts within predetermined limits, and the wabbling motion imparted to the valve keeps the valve head and its seat clean at all times; yet this movement is confined 5 to such limits as to assure proper seating, thus resulting in highly efficient operation.

Were the float guided so as to maintain the same in substantially vertical position and at the same time were the float exposed 10 to the impact of the inflowing fluids through the inlet 13 an excessive amount of friction would result between the vertical moving float and its guiding means, due to the binding effect resulting from the tendency of the 15 float to be forced in a lateral direction, or a tendency to unseat the valve would result, causing clattering. The offset portion 12' is provided and is made of such dimensions that the inflowing liquids do not forcibly 20 strike the side of the float and the impact due to the gaseous portions becomes small. The use of this offset 12' therefore permits the float and valve to be guided within reasonably close limits without creating 25 objectionable friction or rendering the operation inefficient as is frequently the case in known constructions, and at the same time permits a sufficient wabbling motion to assure keeping the valve and its seat clean at 30 all times, resulting in perfect seating.

The operation of the device is obvious from the above description. Briefly it is as follows:

The discharge from the heating system, 35 consisting mainly of condensed steam, steam and air, enter at the inlet 13 and pass into the casing 1. The liquid portions trickle down the side of the offset 12' while the gaseous portions rise to the top of the casing 40 and flow through the annular space 15 and the spaces between the float and the top of the casing and enter the stem 5, a free passage around or through the guiding means being provided as previously explained. 45 The gaseous portions pass downwardly through the stem 5 and valve 6 and are discharged through opening 8. When a sufficient quantity of condensate has collected in the bottom of the casing to raise 50 the float 4, the same rises, opening valve 6 and allows the condensate to be discharged. As soon, however, as a sufficient quantity 55 of the condensate has escaped to allow the float to descend so that the valve 6 contacts with its seat, said valve cuts off further escape and remains seated until enough condensate has been again collected to raise the 60 float 4. It is thus seen that a constantly open passage for the gases and vapors is provided while the liquid portions are intermittently discharged by the opening of valve 6.

The valve 9 is opened from time to time to permit a flow of liquid through the passage 65 10 for the purpose of removing any

sediment which has collected in the trough 12, or to provide a free passage whenever desired as previously described.

I claim:

1. A relief valve comprising a casing, the 70 bottom of said casing having an opening surrounded by a valve seat, a valve coacting with said valve seat, means freely and loosely mounted in said casing responsive to the level of the liquid therein for controlling said valve, said casing having an unobstructed baffleless offset portion of sufficient size at the side thereof for admitting fluids thereto whereby the admission of said fluids will not cause objectionable deflection of the 75 80 said controlling means and valve.

2. A relief valve comprising a casing, the bottom of said casing having a discharge opening, an annular rib surrounding said opening and provided with a valve seat, a valve coacting with said seat, a freely and loosely mounted float attached to said valve, 85 said casing having an unobstructed baffleless offset portion at the side thereof forming a part of the casing proper for admitting fluids into the said casing, the offset portion being of sufficient size to permit the ingress of liquid into the casing without forcibly striking the float.

3. A relief valve comprising a casing, the 90 bottom of said casing having a discharge port provided with a valve seat, a valve coacting with said seat, a float controlling said valve, the valve being connected to the top of said float by a stem provided with an open passage extending through the entire length of the stem and valve, means interposed between the top of the casing and float to limit the upward movement of the float but spacing the said top and float so 105 as to permit the flow of gaseous medium to the passage in the valve stem, said casing having an offset portion of sufficient size to admit liquid thereto without forcibly impinging on the said float.

4. A relief valve comprising a casing, the bottom of said casing having a discharge port provided with a valve seat, a valve coacting with said seat, a float controlling said valve, the valve being connected to the 110 top of said float by a stem provided with an open passage extending entirely through the stem and valve, means interposed between the top of the casing and float to limit the upward movement of the float but 115 spacing the said top and float so as to permit the flow of gaseous medium to the passage in the valve stem, guiding means depending from the top of the casing and loosely fitting the passage in said valve 120 stem, said casing having an offset portion of sufficient size to admit liquid thereto, without 125 forcibly impinging on the said float.

5. A relief valve comprising a casing, 130

the bottom of said casing having a discharge opening, an annular rib surrounding said opening and provided with a valve seat, a conical valve coacting with the said seat, 5 a freely and loosely mounted float attached to said valve, said casing having an offset unobstructed baffleless portion at the side thereof for admitting fluids into said casing, the offset portion being of sufficient 10 size to permit the ingress of liquid into the casing without forcibly striking the float, a hollow extension depending from the bottom of the casing and surrounding the discharge opening and a valve controlled by- 15 pass extending through the bottom into the interior of said extension.

6. A relief valve comprising a casing, the bottom of said casing having a discharge port provided with a valve seat, a valve 20 coacting with said seat, a float controlling said valve, the valve being connected to the top of said float by a stem provided with an open passage extending through the stem and valve, means interposed between the top 25 of the casing and float to limit the upward movement of the float but spacing the said top and float so as to permit the flow of gaseous medium to the passage in the valve stem, guiding means depending from the

top of the casing and loosely fitting and 30 freely movable in the passage in said valve stem so as to permit lateral movement of the float within predetermined limits, said casing having an offset portion of sufficient size to admit liquid thereto without forcibly impinging on the said float. 35

7. A relief valve comprising a casing, the bottom of said casing having a discharge port provided with a valve seat, a float 40 controlling said valve, the valve being connected to the top of said float by a stem provided with an open passage extending through the stem and valve, spaced lugs depending from the top of the casing and adapted to abut said float to limit the upward movement of the float but spacing the said top and float so as to permit the flow of gaseous medium to the passage in the valve stem, said casing having an offset 45 portion of sufficient size to admit fluids thereto without forcibly impinging on the said float. 50

In testimony whereof, I sign my name.

ARNOLD W. MILLER.
